Primary Examiner—Jane E. Corrigan

[57] CLAIM

The ornamental design for a weight for venetian blind
cords, as shown and described.

DESCRIPTION

FIG. 1 is a front elevational view of a weight for venetian
blind cords showing our new design, the rear being
identical;

FIG. 2 is a side elevational view;

FIG. 3 is a top plan view thereof; and

FIG. 4 is a bottom plan view thereof.
